(57) **CLAIM**

The ornamental design for a refueling tank as shown and described.

DESCRIPTION

FIG. 1 is a first perspective view of the refueling tank; FIG. 2 is a second perspective view of the refueling tank; FIG. 3 is a third perspective view of the refueling tank; FIG. 4 is a fourth perspective view of the refueling tank; FIG. 5 is a first side elevation of the refueling tank; FIG. 6 is a second side elevation of the refueling tank; FIG. 7 is a top plan view of the refueling tank; FIG. 8 is a bottom plan view of the refueling tank; FIG. 9 is a left side view of the refueling tank; and, FIG. 10 is a right side view of the refueling tank.

The broken-lines shown in the drawings illustrate features of the refueling tank that form no part of the claimed design.
